Nelson M. Howard

UNITED STATES PATENT OFFICE.

HARVEY L. GLIDDEN, OF NEEDHAM HEIGHTS, MASSACHUSETTS, ASSIGNOR TO UNITED SHOE MACHINERY CORPORATION, OF PATERSON, NEW JERSEY, A CORPORATION OF NEW JERSEY.

SHOE RACK.

Application filed June 18, 1921. Serial No. 473,569.

To all whom it may concern:

Be it known that I, HARVEY L. GLIDDEN, a citizen of the United States, residing at Needham Heights, in the county of Norfolk 5 and State of Massachusetts, have invented certain Improvements in Shoe Racks, of which the following description, in connection with the accompanying drawings, is a specification, like reference characters on the drawings indicating like parts in the several figures.

This invention relates to shoe racks used in shoe factories to convey shoes from one operating position to another, or to store 15 them between shoemaking operations during their manufacture.

It is necessary, especially in the case of fancy women's shoes known as "millinery shoes", to hold the shoes in such a way that 20 they will be protected from dirt or from damage caused by striking one another or other objects. A common way of seeking this result is by putting the shoes on trays mounted as shelves in shoe racks, the trays 25 being equipped in one way or another to protect the shoes as by having pockets for individual shoes in order to keep the shoes from coming in contact with one another, which may be felt lined, or by being covered 30 with sheets of paper to keep the shoes clean.

This practice is accompanied by the serious disadvantage that these trays pick up quantities of dust and dirt which are normally floating in the air of a shoe factory and it 35 is actually impossible to keep them clean for as much as an hour at a time. This practice also has the disadvantage of making it impossible to secure a second condition which is that a shoe rack, at certain 40 stages in the manufacture of certain types of shoes, should be so arranged that it will permit free circulation of air around the shoes in order to dry them out, thereby permitting an earlier removal of the lasts from 45 the shoes. The shelf structure described above impedes free circulation of air and frequently makes a difference of twenty-four hours in the period during which it is necessary for the lasts to remain in the shoes to 50 set them properly.

Another largely successful attempt to solve this problem is found in the so-called

pin rack. This rack comprises a so-called pin bar extending longitudinally of the rack having pins extending laterally therefrom 55 in direct contact with which the shoes rest. Such racks, however, have failed to give entire satisfaction under certain conditions of work because the pins themselves bruise and damage many sufficiently delicate shoe 60 fabrics when placed against them.

In view of these conditions, it is an object of the present invention to provide a shoe rack which shall possess among others the advantages above described as desirable 65 without being subject to the disadvantages noted.

An important feature of the invention consists in a shoe rack equipped with a pin bar the pins of which are adapted to enter 70 the jack pin holes in the lasts, the bar also having means such as a shoulder adapted to cooperate with the upper part of the last cone to prevent rotation of the lasts on the pins. This construction supports the shoe 75 out of contact with any part of the rack with substantial rigidity, preventing rotation of the last on the pin so that accidental contact between adjacent shoes is impossible and at the same time provides for free circulation of the air whereby the shoes may 80 be rapidly dried.

These and other features of the invention, including certain combinations and arrangements of parts, will be understood from the 85 following description of a preferred embodiment thereof selected for purposes of illustration and shown in the accompanying drawings in which,

Fig. 1 is a side elevation of a rack embodying the present invention, and

Fig. 2 is a perspective of a detail.

The frame of the rack may be made in any desired manner, a practical, convenient form of metal frame being shown in the drawing. 95 This comprises a bottom frame 10 upon which are mounted casters 12 and to which are braced by diagonals 14 end frames 16 having cross bars 18 suitably spaced and in convenient number and in registration 100 on the two end frames. Fastened to the corresponding cross bars 18 in any convenient manner as by bolts 20 are the so-called pin bars 22. These bars are normally made

of wood and are shown as of square cross section, scarfed on the ends as at 24 so as to be supported with their diagonals vertically and horizontally, thereby presenting 5 two obliquely and upwardly directed faces 26 and 28. These faces are notched at regular intervals as shown at 30, thus presenting shoulders 31, the notches alternating on opposite sides of the bar and being perhaps 3 10 inch deep. At about the center of each notch is driven a cylindrical pin 32 projecting perhaps two inches and being of a diameter appropriate for the reception into the ordinary jack pin thimble of a last. The 15 width of the notches 30 is slightly greater than the thickness of the top of the cone of the last the use of which is contemplated in the rack. The lasts are placed upon the pins as shown in Fig. 2 with the cone lying 20 in the notch and are thus supported in position, the engagement between the cone of the last and the shoulders 31 preventing any substantial rotation on the pin so that the shoes on the lasts can not contact with each 25 other and become bruised or damaged. The rack as shown is, of course, adapted only for Oxford shoes from the tops of which the lasts project somewhat. The arrangement of the pins upon successive pin bars from the 30 top to the bottom of the rack is alternating as shown in Fig. 1 so that a shoe on one pin bar will not come directly above the corresponding shoe on the next lower pin bar. This feature facilitates the entry and removal of shoes and insures a greater separation between individual shoes, thereby minimizing risk of damage. It is thus seen that 35 my new rack will support shoes so that they cannot come in contact with each other or 40 with the rack parts, and at the same time permits absolute freedom of air circulation around them.

The notch 30 is the preferred means of preventing rotation of the lasts on the pin 45 32, but other simple means for providing the projecting shoulder can be used without departing from the spirit of the invention. For example, the notch may be omitted and one or more auxiliary pins driven alongside 50 the pin 32. Such pins may be parallel to the pin 32 as at 34, or bent outwardly to conform to the taper of the last cone, as at 36.

Having described my invention, what I

claim as new and desire to secure by Letters Patent of the United States is:—

1. A shoe rack comprising a pin bar having a pin adapted to enter the jack pin hole of a last to support it, the bar being also equipped with a member arranged to contact with the cone of the last to prevent rotation on the pin. 60

2. A shoe rack comprising a pin bar having a pin adapted to enter the jack pin hole of a last to support it, the bar being also equipped with an outwardly projecting 65 shoulder arranged to prevent rotation of the last on the pin.

3. A shoe rack comprising a frame having a pin bar having notches of approximately the width of the upper part of a last cone, 70 and pins in the notches arranged to engage the jack pin thimbles of the lasts.

4. A pin bar for a shoe rack having a countersunk portion approximately fitting the upper part of a last cone, and a pin projecting from said countersunk portion arranged to enter the jack pin hole of the last whereby the last is supported without freedom to rotate on the pin. 75

5. A pin bar for a shoe rack formed of a bar of rectangular cross section arranged with its diagonals substantially vertical and horizontal, the upward oblique faces of the bar being notched to a width substantially equal to that of the top of a last cone, each 85 notch having a pin projecting upwardly therefrom adapted to engage the jack pin hole of the last, thereby supporting it without freedom to turn on the pin.

6. A shoe rack having a vertically arranged series of pin bars of square cross-section arranged with their diagonals vertical and horizontal, their upwardly facing surfaces equipped with alternately arranged slots having pins projecting therefrom to 90 enter the jack pin holes of lasts, the widths of the slots being arranged to receive the tops of the cones of the lasts to prevent rotation on the pins, the pins alternating on both sides of each bar and alternating from side 100 to side on alternate bars, substantially as shown.

In testimony whereof I have signed my name to this specification.

HARVEY L. GLIDDEN.
